The ornamental design for a rear bolster as shown and described.

DESCRIPTION

FIG. 1 is a top, rear, left side perspective view of a rear bolster according to my new design.

FIG. 2 is a rear view thereof.

FIG. 3 is a front view thereof.

FIG. 4 is a top view thereof.

FIG. 5 is a bottom view thereof.

FIG. 6 is a right side view thereof; and,

FIG. 7 is a left side view thereof.

The dash-dash broken lines illustrate portions of the rear bolster which form no part of the claimed design. The dash-dot broken lines depict a boundary of the claim and forms no part of the claimed design.
